FABRIK WEISSENSTEIN G. M. B. H., OF CARINTHIA, AUSTRIA

STABILIZED PEROXIDE SOLUTION

No Drawing. Application filed October 12, 1927, Serial No. 225,834, and in Austria September 16, 1926.

This invention relates to the preservation and use of peroxide solutions. It has for its object the preparation of peroxide solutions which are stabilized against decomposition 5 during transportation and storage and which at the same time contain agents which will activate the action of the peroxide during use.

Peroxide solutions have been stabilized 10 prior to use by the addition of various organic materials such as alcohol, urea, barbituric acid, acetanilid, aceto-p-phenetidid, and the like. Furthermore various inorganic materials have been added to bleach baths, 15 for example, which tend to conserve the oxygen and activate or catalyze the peroxide action; the oxygen loss from the baths, however, has remained high. In these practices, only the stabilization alone of solutions during transportation etc. has been effected by 20 the additions at the time of manufacture, while the second activating action is secured by additions to the bleach bath, and the like.

I have found that for use in bleaching peroxide solutions may be stabilized by any of 25 the above substances, but that the stabilizer causes a lowering of the bleaching power. On the other hand, I have found that activated peroxide bleach baths often produce 30 good bleaching effects but that the consumption of active oxygen is high.

I have now discovered that peroxide solutions, specifically hydrogen peroxide solutions, can be prepared which are not only 35 stabilized against decomposition during shipment, storage, and dilution precedent to use, but the bleaching action is also activated during use so that the loss of unused oxygen is low. This I accomplish by the addition 40 to the peroxide solution, at the time of manufacture, of one or more of each of a stabilizing and activating substance. I have found during the use of such solutions as for example in bleaching, that the stabilizing and 45 oxygen activating substances act reciprocally on each other to assist in their respective specific actions.

I have found that hydrogen peroxide solutions containing a plurality of such materials, 50 i. e., one or more of each of a stabilizer and

an activator are especially valuable. Hydrogen peroxide solutions containing such combinations of reciprocally acting compounds suffer practically no decomposition, or loss of unused active oxygen from the action of the solid materials which are often permanently bound to the fibers of material to be bleached, and which ordinarily would produce a decided loss by catalytic action. Finally, I have found, that these peroxide 55 solutions have the same chemical action in bleaching as ordinary solutions of peroxide alone; cause very little loss of active oxygen from the actual bleaching process; are stable to shipment and storage in warm climates; 60 do not injure materials to be bleached; may be diluted for use without loss of active oxygen; eliminate the necessity for special additions at the time of preparing a bleaching bath; give better bleaching results with less 65 peroxide consumption; and may be used while containing the same additions in the same proportions for every type of bleaching.

The results mentioned above may be obtained to an extraordinary degree by the simultaneous addition to peroxide solutions of a combination such as sodium pyrophosphate, sodium silicate, and sodium chloride, or of various combinations of sodium pyrophosphate, sodium chloride, chlorinated hydrocarbons, colloidal materials, Turkey red oil, water glass, etc. However, I wish it expressly understood that the present invention is not to be limited to these specific additions 75 nor to the examples given below. On the other hand, any combination of stabilizers and activators for peroxide solutions resulting in a mutual action which increases the power of each during the reaction of the 80 peroxide with other substances, and which produces a stabilizing action on the solution when not in use, should be considered as belonging to the present invention.

The following are given as examples: 85

Example 1

To a 30% solution of hydrogen peroxide there is added 2.5% of $\text{Na}_4\text{P}_2\text{O}_7 \cdot 10\text{H}_2\text{O}$ and 1% NaCl , the normal weakly acid reaction is 100

restored by the addition of acid, for example sulfuric. The commercial solution thus prepared shows a loss from the original active oxygen content of only 0.23% after heating 5 to 70° C. for several hours. The loss was as high as 1% for the same solution with the addition of 2.5% of sodium pyrophosphate alone. With NaCl as the only addition the loss was greater under the same conditions. 10 A solution prepared as in this example showed practically no loss of active oxygen after being kept six weeks at 35 to 40° C. Such a solution diluted to 3% and kept either acid, neutral or alkaline showed a better 15 bleaching effect upon straw after six hours at 70° C. than a 3% solution of peroxide alone. The consumption of peroxide was about 15 to 17% of the original, whereas over 80% of the original peroxide was used in an 20 alkaline 3% solution of ordinary peroxide.

Example 2

To a 30% solution of hydrogen peroxide there was added 2.5% of $Na_4P_2O_7 \cdot 1OH_2O$, 25 0.5% NaCl, and 1% of water glass. The slight acid reaction of the solution was restored with phosphoric acid. After heating at 70° C. for several hours scarcely any decomposition had resulted, whereas a solution of 30 peroxide of the same concentration but with no addition showed a loss of 2.3%. A solution made up according to this example and diluted to 0.5% showed only 10 to 20% decomposition of peroxide with a good bleaching 35 effect on wool at 40 to 50° C. for about five hours. However, a peroxide solution of the same concentration, which had not been treated as the above, decomposed quickly and completely without any noteworthy 40 bleaching action.

Example 3

An extraordinary bleach solution is produced from a solution of 30% hydrogen peroxide containing 0.2% $Na_4P_2O_7 \cdot 1OH_2O$, 0.5% NaCl, 1% Turkey red oil, and 1% water glass. The solution is made slightly acid with phosphoric acid. This solution is also stable toward shipment and practically no loss of peroxide could be detected after heating it three 50 hours at 70° C.

Some felt was bleached by diluting this 30% solution to 2%, making it slightly ammoniacal, and heating to 50° C. for five hours. 55 The bleaching action was very good and only about 20% of the original peroxide was consumed.

Claims:

- 60 1. Peroxide solution containing sodium pyrophosphate and an alkali metal halide.
2. Hydrogen peroxide solution containing sodium pyrophosphate and sodium chloride.
3. Hydrogen peroxide solution containing sodium pyrophosphate, sodium chloride and 65 a colloidal material.

4. Hydrogen peroxide solution containing sodium pyrophosphate, sodium chloride and one of the colloidal materials, sodium silicate, Turkey red oil and soap.

5. Hydrogen peroxide solution containing 70 sodium pyrophosphate, sodium chloride, sodium silicate and Turkey red oil.

Signed at Vienna, Austria, this 27th day of September, 1927.
